UNITED STATES PATENT OFFICE.

HENRY A. ROBERTS, OF DETROIT, MICHIGAN, ASSIGNOR TO GUSTAVUS F. SWIFT, OF CHICAGO, ILLINOIS.

REFRIGERATING-ROOM.

SPECIFICATION forming part of Letters Patent No. 256,052, dated April 4, 1882.

Application filed October 6, 1880. (No model.)

To all whom it may concern:

Be it known that I, HENRY A. ROBERTS, of Detroit, in the county of Wayne and State of Michigan, have invented a new and useful Improvement in Refrigerating-Rooms, of which the following is a specification.

My invention relates chiefly to the construction of rooms on board ships for the purpose of transporting fresh meats and other perishable articles, whereby economy of space is secured, and at the same time the articles are transported without danger of loss; and it consists, first, in a chamber situated between the decks of the vessel and divided into vertical preserving-compartments having ice-receptacles, and into vertical compartments for the storage of the surplus ice adjoining the preserving-compartments, all of such apartments being disconnected and having independent doors; and, second, in the combination of the same parts with the ice-receptacle constructed to open into the ice-storage compartments, all as hereinafter explained. This method of construction tends to keep the outside of the preserving-chambers cool, and also facilitates the charging of the ice-receptacles.

In the drawings, Figure 1 is a top view of my improved refrigerating-room on the line of the rack or floor of the ice-receptacle, and Fig. 30 2 is a vertical section of the same.

A represents one deck of a ship, and B represents another deck, and between these two decks my refrigerating-room C is built in any suitable manner.

35 D is a compartment or preserving-chamber within this room, having an ice-receptacle, H, which may be of any desired form or material.

F is a door for affording access to the preserving-chamber D.

40 E is a compartment for the storage of ice, adjoining the preserving-chamber D, but divided from it by the partition J. A door, I, in partition J affords access from compartment E to ice-receptacle H, and closes all connection between compartment E and preserving-chamber D.

G is a hatch or door for admitting entrance to compartment E.

The surplus ice is stored in compartment E, and the ice-receptacle H can be charged when necessary by opening the door I. If the ice-receptacle be a tight metal box, it should have a funnel or neck opening through the partition J at the top of the box, and closed by a stopper. The door I should be kept closed, except when opened for charging the ice-receptacle H.

If the room C should be too large to be divided into one refrigerating-compartment and one ice-storage compartment, it may be subdivided into as many such refrigerating-compartments, with ice-storage compartments between them, as is necessary to make the refrigerating-compartments of proper size.

I do not claim any particular form of ice-receptacle, nor any particular manner of constructing the walls of room C; but

What I claim as my invention, and desire to secure by Letters Patent, is—

1. In combination with the preserving-compartment (one or more) of a refrigerator and a receptacle (one or more) for the refrigerant, a compartment (one or more) for the storage of surplus ice, arranged with relation to each other substantially as described.

2. An inclosed chamber divided into vertical preserving or refrigerating compartments having receptacles for the ice or other refrigerant, and vertical ice-storage compartments adjoining such preserving-compartments, all of such compartments being disconnected and having independent doors, substantially as and for the purpose set forth.

3. In combination, vertical preserving-compartments, vertical compartments for the storage of surplus ice adjoining such preserving-compartments and not connected therewith, and receptacles for the refrigerant opening into such storage-compartments, substantially as described and shown.

HENRY A. ROBERTS.
